APPLICATION OF LIQUIDS TO MATERIALS

Albert Mellor and William Pool, Spondon, near Derby, England, assignors to Celanese Corporation of America, a corporation of Delaware

Application January 30, 1937, Serial No. 123,102
In Great Britain February 6, 1936

2 Claims. (Cl. 68—22)

This invention relates to the application of liquids to materials, particularly materials in sheet or web form, and is especially concerned with the application of liquids comprising solutions of substances in volatile solvents.

The object of the invention is to enable materials in sheet or web form to be given substantially uniform treatment with the liquid to be applied.

10 According to the invention, liquid is applied to a web or sheet of material by means of a pad mangle comprising a pair of rollers arranged side by side so that each depends into a trough for the reception of the liquid to be applied, the rollers forming a nip at or only slightly above the level of the liquid in the trough. The web or sheet is passed through the trough and upwards through the nip, the material being impregnated by its passage through the liquid, and the rollers expressing surplus liquid from the material without there being an opportunity for the liquid to run in streams over the material. The material leaves the nip with a substantially uniform content of liquid. Further, the rotation of the rollers in the liquid prevents any substance dissolved in the liquid from being left by evaporation in solid or concentrated form on the rollers and subsequently printed on to the impregnated fabric.

20 One or both rollers may be rubber- or fabric-covered to assist in uniform impregnation of the material. As an alternative, the rollers may serve as a means for supporting endless bands which are carried repeatedly through the liquid, and through the nip of the rollers. Such bands may, if desired, be so mounted as to have the effect of extending the nip for some distance upwardly above the rollers so as to maintain the fabric under treatment for a longer period in contact with surfaces charged with the liquid.

25 The invention is particularly suitable for the carrying out of the process described in U. S. application S. No. 124,138 filed February 4, 1937, corresponding to British application No. 3628/36 according to which substances, e. g. dyestuff are applied to materials such as cellulose acetate or other cellulose ester or ether textile materials in solution in volatile organic solvents the materials being afterwards subjected to the action of vapours of an organic solvent. Thus, the impregnated material may be dried in any convenient manner, means being provided if necessary for recovery of solvent expelled from the material. For this purpose the drying may be accomplished with great advantage in the ap-

paratus described in U. S. application S. No. 124,139 filed February 4, 1937, corresponding to British application No. 3630/36 by means of which solvent removal is effected by means of superheated vapours of the solvent during part of the travel of the material, while during the remainder of its travel the drying of the material is completed with the aid of a gas, e. g. warm air operating in conjunction with suitable recovery means, e. g. a carbon recovery plant.

30 With the arrangement described above, impregnation, and if desired, vapour treatment, and drying are carried out rapidly in a continuous manner.

35 By way of example a form of apparatus according to the invention will now be described in greater detail with reference to the accompanying diagrammatic drawings, of which

Fig. 1 is a part cross-sectional side elevation of a machine for applying liquid to sheet material;

Fig. 2 is a part cross-sectional front elevation taken on the line 2—2 of Fig. 1; and

Fig. 3 is a part cross-sectional elevation of a detail of Figs. 1 and 2.

40 Referring to Fig. 1, fabric 4 unwinding from a roll 5 which is rotatably supported by brackets 6 outstanding from the machine frame 7 (shown in dotted line) passes upwardly to and around a roller 8. From the roller 8 the fabric passes around guide rollers 9 operating in a trough 10 and is directed upwardly from the last of these rollers to the nip of a pad mangle comprising a pair of rubber-covered rollers 11. The trough 10 is filled with liquid (e. g. a dye liquor) to a level (indicated at 12) slightly below the nip of the mangle rollers 11.

45 In its passage round the submerged guide rollers 9, the fabric becomes thoroughly impregnated and remains so up to the point at which expression of the liquid by the mangle rollers 11 begins with the result that there is no opportunity for liquid to run down the fabric in streams. The rotation of the rollers 11 in the liquid, moreover, keeps the rollers thoroughly wetted and provides no opportunity for the concentration on the surfaces of the rollers of any substance dissolved in the liquid by evaporation of the liquid.

50 Thus, the fabric is not subjected to streams of liquid or other concentrations of substance dissolved in the liquid that might tend to produce uneven effects on the fabric, but leaves the nip rollers with a substantially uniform content of liquid. A uniform treatment of the fabric results. For example, if the liquid contains a dis-

solved dyestuff, subsequent drying leaves the fabric substantially uniformly treated with the dyestuff.

In order to facilitate the starting of the liquid-applying operation and to allow of the fabric 4 being passed over the guide rollers 9 without difficulty the trough 10 can be lowered from operative position. Thus, the trough is supported by vertical standards 14 which are pivotally supported both from the machine frame by links 15 and from a rotatable shaft 16 by links 17. The links 17, which are fixed to the shaft 16, extend beyond the shaft and form levers, and are provided near their outer ends with balance weights 18 the moment of which about the shaft 16 is sufficient to maintain the trough 10 in the raised or operative, position.

A worm wheel 20 is fixed to the shaft 16 and is engaged by a worm (not shown) housed in a casing 21, the worm being secured to a shaft 22 which is rotatable by a hand-wheel 23. In order to lower the trough 10 from the operative position (i. e. from the position shown in the drawings) the hand-wheel 23 is rotated in the appropriate direction, the resulting rotation of the shaft 16 by the worm wheel 20 causing the links 15, 17 to rotate about their pivots to lower the trough. After the fabric 4 has been passed over the guide rollers 9 and it is desired to start the liquid-applying operation, the hand-wheel 23 is rotated in the reverse direction to raise the trough 10 into operative position.

The left-hand mangle roller 11 is supported in movable bearings 25 (one shown in Fig. 1) which are slidably mounted on blocks 26 formed on the machine frame. Each bearing 25 is urged to the right by a pressure bar 27 so as to set up pressure between the two rollers 11, the bar itself being pressed by a lever 30 to which the bar is connected by a pivotally mounted threaded block 31. The lever 30 is urged to rotate clockwise about its pivot 32 by a bell-crank lever 33 which is weighted at 34 and connected to the lever 30 by a link 35. The pressure between the mangle rollers 11 can quickly be released (e. g. when it is desired to pass the leading end of a piece of fabric between the rollers) by a hand lever 36, anti-clockwise rotation of which brings about similar rotation of the bell-crank lever 33 by means of a lifting cam 37 which is connected to the hand-lever and disposed beneath the bell-crank lever. The degree of pressure between the mangle rollers 11 may be adjusted by suitably varying the weights 34. The pressure bars 27 can be rotated within the blocks 31 by means of a hand wheel 40 fixed to each bar.

Liquid is fed to the trough 10 from a closed container 41, (see Figs. 2 and 3), the container being suspended in inverted position over a covered extension 42 of the trough and provided with a feed-pipe 43. As the liquid in the trough is consumed, the fall in its level permits air to pass through an opening 44 in the cover of the extension 42 and through a valve 45, pipe 46 and pipe 47 to a point above the level 48 of the liquid in the container 41 with the result that liquid is allowed to flow from the container to the exten-

sion 42. When, however, the liquid in the trough reaches the desired level a float and needle device 50 in the extension 42 rises and closes the valve 45. The closing of the valve stops the flow of air into the container 41 and the flow of liquid from the container consequently ceases. The action of the float and needle device 50 is fully automatic and the device maintains a substantially constant level of liquid in the trough 10. The pipe 46 is flexible in order to allow of the lowering and raising of the trough 10 (and extension 42) without disturbing the liquid feeding apparatus.

After recharging the container 41 any liquid in the air pipe 47 can be drained from the pipe by a three-way cock 51 and drain pipe 52 which connects the cock with the pipe 43. Thus, to ensure that the pipe 47 is freed from liquid at the commencement of the liquid-applying operation the cock 51 is turned to connect the pipe 47 with the drain 52. When the pipe 47 is drained the cock is turned to connect the flexible pipe 46 with pipe 47 (as shown in Fig. 3) and a cock 53 in the pipe 43 is opened to allow the feed of liquid to the trough to commence. During the recharging of the container, the cock 51 is turned into the third position to disconnect the pipe 47 from the flexible pipe 46, thus preventing any liquid which may be poured into the pipe 47 from passing down the pipe 46.

Having described our invention, what we desire to secure by Letters Patent is:

1. Apparatus for applying liquid to a web or sheet of material, comprising a pair of mangle rollers, means for rotatably mounting said rollers side-by-side to form a nip, a trough for the reception of the liquid, movable means for supporting said trough beneath the rollers, means for controlling said supporting means, said controlling means being adapted to move said supporting means so as to raise the trough into a position such that the rollers depend into the trough and form the nip close to the level of the liquid in the trough, and to lower the trough from such position, a liquid supply connected to the trough, and means controlling the flow of liquid from the supply to the trough and adapted to maintain a substantially constant level of liquid in the trough.

2. Apparatus for applying liquid to a web or sheet of material, comprising a pair of rubber-covered mangle rollers, means for rotatably mounting said rollers side-by-side to form a nip, a trough for the reception of the liquid, means for mounting said trough beneath the rollers in a position such that the rollers depend into the trough and form the nip close to the level of the liquid in the trough, a guide roller positioned in the trough and adapted to direct the web or sheet of material to the nip of the rollers, a liquid supply, a feed pipe connecting said supply to said trough, and means controlling the feed of liquid from the supply to the trough and adapted to maintain a substantially constant level of liquid in the trough.
